UNITED STATES PATENT OFFICE.

STEWART L. MOORE, JR., OF BALTIMORE, MARYLAND, ASSIGNOR TO LOCKE INSULATOR CORPORATION, OF BALTIMORE, MARYLAND, A CORPORATION OF MARYLAND.

HOLE-CUTTING MACHINE.

Application filed May 19, 1926; Serial No. 110,302. Renewed February 8, 1928.

The invention relates to machines for cutting holes in the formation of insulators of the Hewlett type.

The primary object of the invention, generally stated, is to provide a machine by means of which interlinking curved passages may be cut in insulators while they are still in a green or plastic condition, the cutting being done accurately and uniformly.

10 An important object of the invention is to provide a device for this purpose so constructed and arranged that the ends of the passages will be flared for the accommodation and to permit slight play of the suspension links which are employed for connecting a series of insulators to form a string.

It is well known that insulators of the Hewlett type are formed with interlinking curved passages, one opening out at the top and the other at the bottom. The suspension links are generally of substantially U-shape and are slid into the passages. It is a matter of importance that the passages be true in form and that they have smooth walls in order to 20 avoid high spots which, when the links are in place, would localize or concentrate the strain instead of permitting it to be distributed. To facilitate the insertion of the links in the passages the passages should have flaring entrances which serve the additional purpose of permitting a certain amount of play of the links with respect to the insulators so that the parts may accommodate themselves 25 to the line of strain. It has been proposed to 30 cut the passages by hand but obviously this is bound to be a slow and laborious operation. Furthermore, regardless of the exact method of cutting there is a tendency for the clay to tear away at the ends of the passages, resulting in inequalities and minus spots which are naturally objectionable.

It is with the above facts in view that I have designed the present invention which has for a more specific object the provision 45 of a machine by means of which interlinking curved passages may be cut not only quickly, easily and accurately but which will form the desirable flaring openings and leave the walls smooth and clean.

50 Another object of the invention is the provision of a machine for this purpose provided with or embodying peculiarly constructed cutting members formed of relatively movable sections so as to be capable of cutting

a passage of more than mere semicircular 55 shape.

Still another object of the invention is to provide a novel operating means including a system of links and levers for moving the cutters and the relatively movable sections 60 thereof, the different steps in the movement being properly timed to effect the proper cutting action so that passages of the desired shape will be formed, adjustments being, moreover, provided for regulating the throw 65 of the movable parts.

Yet another object of the invention is the provision of a machine of this character in which the cutters will move toward each other during the cutting action, the cutters coming 70 to rest in end to end relation, the machine further embodying an important feature, namely, means for puncturing the slight division wall left between the ends of the cutters at the completion of their stroke, the puncturing preventing a suction effect upon withdrawal of the cutters so that distortion of the 75 passages will be avoided.

An additional object of the invention is to provide a cutting machine of this type provided with means whereby the entire cutting mechanism may be lifted bodily away from the insulator to a sufficient height that insulators may be placed in position, cut, inverted and turned for additional cutting 80 without any interference whatsoever with any of the moving parts.

To the attainment of the foregoing and other objects and advantages such as comparative simplicity, ease in operation and efficiency in action, the invention preferably 90 consists in the construction, combination and arrangement of parts to be hereinafter more fully described and claimed, and illustrated in the accompanying drawings in which:

95 Figure 1 is a front elevation of the complete machine with the cutting mechanism shown in its highest position.

Figure 2 is a side elevation with the cutting mechanism shown in lowered position 100 at the beginning of a cut.

Figure 3 is a vertical section taken in a plane at right angles to Figure 1 and showing the cutting mechanism in the act of starting its cut,

105 Figure 4 is a similar view showing the position of the parts at the completion of a cut by full lines, the nearly final position

being shown by dotted lines for illustrating the independent movement of certain cutter sections with respect to others.

Figure 5 is a detail sectional view on a larger scale showing one complete cutter in section and illustrating the puncturing or air vent forming means,

Figure 6 is a detail sectional view through the puncturing tool,

10 Figure 7 is a detail cross sectional view through one upper cutter taken on the line 7-7 of Figure 5,

15 Figure 8 is a detail cross section through the upper and lower cutter taken on the line 8-8 of Figure 5,

20 Figure 9 is a detail cross section taken on the line 9-9 of Figure 5 and showing the mounting for the lower cutter.

25 Referring to the drawings in detail I have shown the machine as including a base 1 from which rise suitably mounted guides 2 on which is slidably a carriage structure indicated generally at 3, this carriage being shown as comprising upper and lower members 4 and 5 radiating from a housing 6 and terminating in sectional sleeves 7 and 8, respectively, engaged upon the guides 2. Suitably secured to the lower arms 5 are depending brackets 9 which support the cutting mechanism to be described. The lower sleeve members 8 may be provided with lateral extensions or lugs 10 carrying rods 11 slidable through the base and which might, if preferred, be connected with some suitable treadle mechanism for moving the carriage. 30 Downward movement of the carriage may be limited by stops 12 rising from the base and upward movement is of course limited by a transverse bar or other member 13 which connects the guides 2 at their upper ends. The stops 12 are shown as screwed into place and equipped with lock nuts 14, it being thereby possible to adjust them in case such is necessary.

40 45 For counterbalancing the slidable carriage and all the parts carried thereby and to be described, I may employ a forked lever 15 pivoted as at 16 upon bearing brackets 17, the ends of the lever arms being pivotally connected as at 18 with angular brackets or the like 19 preferably mounted beneath and secured to the extensions or lugs 10 of the sleeves 8. The forked lever 15 may carry any necessary weight or weights 20 (Figure 2), the weight or weights being adjustable and being held in place as by means of set screws 21 or their equivalent.

50 55 At the center of the base 1 may be provided a tubular boss 22 for the reception of a stem 23 depending from a pallet or plate member 24 which carries a support 25 having the proper configuration to conform to the curved surfaces of an insulator 26 in which interlinking curved passages are to be cut. At certain stages in the operation the

insulator must be given a quarter turn and for this reason any suitable means may be provided for permitting the support formed by the parts 23, 24 and 25 to be turned to just this extent and if desired, a stop device or indicator 27 may be provided at one side.

60 As above mentioned, the entire cutting mechanism is supported from the carriage and includes two pairs of angular frame members or yokes 28 and 29 pivoted at opposite sides of the depending brackets 9. The members 28 are formed with extensions or lugs 30 upon which are pivotally and slidably mounted, as by pins 31 and slots 32, intermediate links 33 which are in turn pivotally connected at 34 with the members 29 so that all the members 28 and 29 may be moved together though to different extents. The operating means is here shown as comprising a rack 35 slidable through the housing 6 and having pivoted thereto at 36 rods 37 carrying clevises 38 pivotally connected at 39 with the links 33. The upper ends of the rods 37 are also preferably equipped with clevises 40 and intermediate their ends are turnbuckles 41 for adjusting purposes. Journaled transversely of the upper portion of the frame and mounted in any suitable bearings is a shaft 42 carrying a gear 43 meshing with the rack 35. On one end of the shaft is an operating handle 44 preferably counterbalanced as at 45.

65 Secured to the frame or yoke members 28 are arms 46 which carry cutter members 47 which are of general arcuate shape and which are substantially elliptical in cross section at their ends most remote from the arms 46, the upper portions being cut away at opposite sides as shown at 48, the uncut portions being substantially semi-elliptical in cross section. The purpose of the cutting away at 48 will be hereinafter explained. The end portions of the arms 46 are formed with recesses or concavities 49 conformingly receiving the cutters 47 which are held in place by bolts 50 or the like passing through filler blocks 51 located within the members 47 as clearly indicated in Figure 9, the arms 46 having threaded holes 52 for the reception of the screws or bolts. The arms 46 also carry leaf springs 53 held in place as by screws 54 and bearing against grub or other adjusting screws 55 which pass through the arms 46 as clearly indicated in Figure 5, and the purpose of which will be hereinafter explained though it should be mentioned at this point that these springs are located in such position as to be engaged by nose pieces or projections 56 on the intermediate connecting links 33.

70 75 Carried by the frame or yoke members 29 are arms 57 carrying cutter sections 58 of such size and shape as to fit conformingly within the cut away portions 48 of the cutters 47. The free ends of the arms 57 are preferably convexed as indicated and fit conform-

ingly within the cutter members 58 which are substantially semi-elliptical in cross section. Securing is effected by means of complementary clamp elements or blocks 59 which are concaved at 60 to fit against the members 58. Any suitable screws or bolts 61 pass through the members 59, the members 58 and into threaded holes 62 in the arms 57 so that the parts will be secured.

10 As mentioned in the objects of the invention, an important feature is the provision of means for puncturing the slight partition wall which is certain to remain between the adjacent ends of the cutters 47 after they have completed their stroke. To carry out this detail, I may employ a tubular guide 63 of somewhat curved form carried by the arm 57 and extending within the cutter member or section 58, this guide containing a flexible 20 rod 64 projecting through a hole 65 in the arm 57 and having its upper end projecting considerably thereabove, the lower end carrying a head 66 located beyond the guide 63. This head 66 is capable of limited movement 25 longitudinally of the rod 64, the extent being limited by stops 67 and 68. This head constitutes a species of valve and for this reason it is formed with a bore 69 of slightly greater diameter than the rod 64 to provide an air 30 space or passage about the latter. As this head 66 constitutes the puncturing element it has its forward end preferably beveled or cone shaped as disclosed at 70.

In the operation of the device, it will of course be understood that initially the entire carriage 3 must be in elevated position as shown in Figure 1, this being effected by moving it upwardly by any treadle mechanism connected with the rods 11 or, if preferred, by moving the lever 15. The insulator 26 may then be placed in position upon its support 25 or the support 25 carrying the insulator may be placed upon the base, the latter being probably preferable for the reason that the insulators are handled while in a "green" or plastic condition. The carriage 3 is then caused or permitted to descend, the downward movement being limited by engagement of the ears or lugs 10 with the stops 12. The downward movement of the carriage is sufficient to bring the cutters 47 and 58 immediately adjacent the insulator. When the parts are in this position it will be clear that the cutter members or sections 58 will be spaced from the cutters or sections 47. As shown in Figure 3 it should be observed that the cut-out portions 48 in the cutters 47 extend sufficiently far toward the free ends thereof that the lower ends of the cutters or sections 58 will be curved as clearly indicated, particularly in Figure 3.

The operator then grasps the crank handle 44 and rotates the shaft 42 and gear 43 so that the rack 35 will be moved downwardly. As 65 this downward movement occurs the rod

members 37 will swing outwardly upon the pivot 36, resulting in outward swinging movement of the intermediate links 33 on the pivots 39 and 34, the members 29 being, of course, swung apart or downwardly upon 70 their pivots, the cutter sections 58 of course moving downwardly and outwardly at the same time. As the lower ends of these cutter sections are curved the paths of the free ends will be substantially circular. Owing to the 75 peculiar connection of the members 28 and 29 by means of the links 33 it is evident that the members 28 and 29 will swing outwardly and downwardly to substantially the same extent. Of course even though the links 33 are slotted at 32 the members 28 carrying the 80 cutter members 47 will be moved downwardly to a certain extent and will cut into the insulator along a circular path. As the inner wall of the desired cut to form the passage is 85 not concentric with the outer wall the cutter members 58 and 47 must have relative movement and it is for this reason that the pin and slot connections 31 and 32 are provided. Until the rack bar 35 has moved downwardly 90 to such an extent that the rods 37 are in the position shown by dotted lines in Figure 4 the pins 31 are engaged by the outer ends of the slots 32 and the cutter sections 58 are still spaced away from the sections 47, though the extent has decreased gradually during the 95 entire downward movement of the rack bar on account of the difference in swing of the members 28 and 29.

To limit downward movement of the members 28 at this point, I provide stops such as the upright rods 71 which rise from the base and which are preferably threaded thereinto so as to make adjustment possible. When the rods 37 and other parts have reached the position shown by dotted lines in Figure 4 the extensions 30 on the members 28 engage the stops 71 so that there will be no further downward movement of the members 28. By the time the members 28 have reached this position the cutters 47 will have been forced through the material of the insulator so that the ends thereof will be substantially in engagement there being only a very thin partition wall left uncut.

As the rack 35 continues to move downwardly the links 33 move outwardly owing to the provision of the slots 32 therein. By the time the inner ends of the slots engage against the pins 31 the links 33 are in such position that the nose pieces 56 thereof engage upon the springs 53 which cushion the shock while acting as stops. During this outward movement of the links with respect to the pins 31 the members 29 swing still further 115 outwardly into the position shown by full lines in Figure 4, the cutter sections 58 then entering and fitting within the cut away portions 48 in the cutter members 47. This movement is necessary in order that the mem- 120

bers 58 will move in the proper path to cut the inner wall of the passage.

Of course it is understood that the tubular member 63 carrying the rod 64 and puncturing head 66 is mounted within one of the members 58. When the downward movement of the rack bar is completed so that the assembled cutters are in substantially meeting relation, the operator grasps the rod 64 and forces it downwardly so that the head 66 will be caused to puncture the slight partition wall 72 between the ends of the cutters. As the bore 69 in the puncturing member is of greater diameter than the rod 64 it is clear that an air vent will be provided so that when the crank handle 44 is turned in the reverse direction to move the rack upwardly for restoring the cutting mechanism to initial position the cutters, which then of course have a reverse movement, may be withdrawn from the passages cut thereby without producing any suction which might draw the walls inwardly and cause serious distortion as frequently occurs under ordinary methods. Naturally the clay cut out of the insulator remains within the cutters until forced out by some suitable tool or implement.

After one curved passage has been thus cut the carriage is elevated and the insulator is turned over or inverted with respect to its former position and is, preferably with its holder, given a quarter turn with respect to the base 1, subsequently to which the cutting operation is repeated in a manner identical with that above described so as to form a second passage at right angles to and interlinking with, but of course spaced from, the first formed passage. It is of course evident that any suitable polishing or smoothing tool may be inserted within the passages for removing the slight ragged edge which is all that remains of the partition after the same has been punctured. Subsequent to the cutting the insulator is of course removed from the machine and fired or otherwise treated in the usual manner to produce the finished article.

The above operation is proper to follow and will be carried out if the machine be of such construction as to embody only one set of cutting mechanisms mounted above a supporting stand or table. It is readily conceivable and will be understood by one skilled in the art that it is easily possible to duplicate the structure below the support, there being then two sets of cutting apparatus, one above the table and the other below, the two sets being of course at right angles to each other. It is also easily possible to provide an operative connection between the upper and lower cutting mechanisms so that they will operate simultaneously upon opposite sides of a suitably supported insulator for forming both interlinking curved passages at the

same time or in one operation of the machine. This possibility is not illustrated as it is thought that such an arrangement would readily occur to one versed in this art after obtaining a full comprehension of the structure disclosed. 70

From the foregoing description and a study of the drawings it will be apparent that I have thus provided a very simply constructed and easily operated machine by 75 means of which the necessary interlinking curved passages may be formed in insulators of the Hewlett type, the arrangement being such that the cutting will be accurate and uniform throughout any number of insulators. This last mentioned feature is of great advantage inasmuch as it insures proper fitting, without binding, of the suspension links employed for connecting such insulators in the usual strings. Ample provision has been made for all adjustments which may be found necessary to insure proper throw of the various coacting parts, these adjustments taking care of any possible variations which may occur in the general 80 dimensions or shape of any number of insulators in a certain lot. In fact the device operates to accomplish all the beneficial results desired. 85

While I have shown and described the preferred embodiment of the invention, it should be understood that the details are merely an exemplification of the possibilities and principles involved as I reserve the right to make all such changes in the construction and arrangement of parts as will increase the adaptability or widen the field of utility of the device, provided such modifications constitute no departure from the spirit of the invention or the scope of the claims hereunto 90 appended. 100

Having thus described the invention, I claim:

1. In a machine of the character described, the combination of a supporting structure, means for temporarily mounting an insulator thereon, oppositely arranged curved cutters, and means for moving said cutters in a curved path through the material of the insulator for forming a curved passage therein. 110 115

2. In a machine of the character described, the combination of a supporting structure, a carriage movably mounted thereon, means for temporarily supporting an insulator beneath the carriage, cutting mechanism carried by the carriage and including curved cutting members, and means for moving the cutting members along curved paths for forming a curved passage through the material of the insulator. 120 125

3. In a machine of the character described, the combination of a supporting structure, a carriage movably mounted thereon, means for temporarily supporting an insulator beneath the carriage, cutting mechanism carried by 130

- the carriage and including curved cutting members, and means for moving the cutting members along curved paths for forming a curved passage through the material of the 5 insulator, each cutting member including relatively movable sections.
4. In a machine of the character described, the combination of a supporting structure, a carriage movably mounted thereon, means 10 for temporarily supporting an insulator beneath the carriage, cutting mechanism carried by the carriage and including curved cutting members, and means for moving the cutting members along curved paths for forming a 15 curved passage through the material of the insulator, each cutting member including relatively movable sections whereby the inner and outer walls of the passage will be eccentric.
- 15 5. In a machine of the character described, the combination of a supporting structure, means for temporarily mounting an insulator thereon, oppositely arranged curved cutters, means for moving said cutters in a 20 curved path through the material of the insulator for forming a curved passage therein, and means carried by one cutter for puncturing the slight partition remaining between the ends of the cutters upon the completion 25 of their stroke.
6. In a machine of the character described, a support, means for temporarily mounting an insulator thereon, a pair of curved cutters, means for moving the cutters in a curved 30 path through the material of the insulator whereby the ends of the cutters will substantially contact, a guide within one cutter, and a puncturing means slidable through the guide for puncturing the material remaining 35 between the ends of the cutters at the completion of their stroke.
7. In a machine of the character described, a support, means for temporarily mounting an insulator thereon, a pair of curved cutters, 40 means for moving the cutters in a curved path through the material of the insulator whereby the ends of the cutters will substantially contact, a guide within one cutter, a puncturing means slidable through the guide 45 for puncturing the material remaining between the ends of the cutters at the completion of their stroke, the puncturing means including a rod slidable through the guide, and a head loosely mounted upon the rod for 50 forming an air vent.
8. Means for forming a curved passage 55 through an insulator, comprising a pair of cutters movable in opposite directions in a curved path whereby to substantially meet within the insulator in end to end relation, and a vent forming member movably mounted within one cutter and projectable through the material remaining between the adjacent ends of the cutters.
- 60 65 9. Means for forming a curved passage in an insulator, comprising a pair of curved cutters movable in a curved path in opposite directions to substantially meet within the body of the insulator, and combined penetrating and vent forming means mounted within 70 and carried by one cutter.
10. Means for forming a curved passage in an insulator, comprising a pair of curved cutters movable in a curved path in opposite directions to substantially meet within the 75 body of the insulator, combined penetrating and vent forming means mounted within and carried by one cutter, each cutter including relatively movable sections, and means for moving the sections independently whereby 80 the outer and inner walls of the passage will be eccentric.
11. In a machine for cutting curved passages in insulators, the combination of a relatively stationary supporting structure for 85 holding an insulator, a carriage vertically movably mounted with respect to the supporting structure, means for moving the carriage, curved coacting cutters movably mounted on the carriage, means for moving 90 the cutters.
12. In a machine for cutting curved passages in insulators, the combination of a relatively stationary supporting structure for holding an insulator, a carriage vertically 95 movably mounted with respect to the supporting structure, means for moving the carriage, curved coacting cutters movably mounted on the carriage, means for moving the cutters, the cutters being formed of relatively movable sections, and means for moving the sections simultaneously and relatively.
13. In a machine of the character described, the combination of a supporting structure, members pivotally mounted thereon, cutters carried by said members, and means for swinging said members for moving the cutters in an arcuate path.
14. In a machine for cutting curved passages in insulators, a stationary supporting structure, members pivotally mounted thereon, cutters mounted on said members, and means for swinging said members to move 105 the cutters in an arcuate path into substantially end to end relation.
15. In a machine for cutting curved passages in insulators, a stationary supporting structure, members pivotally mounted thereon, cutters mounted on said members, means 110 for swinging said members to move the cutters in an arcuate path into substantially end to end relation, and vent means carried by one cutter projectable into the other for puncturing the partition left between the 115 cutters.
16. In a machine of the character described, a stationary supporting structure, means for holding an insulator temporarily thereon, a plurality of pairs of members piv- 120
- 65 90 130

oted on the supporting structure, cutter elements carried by said pairs of members, and means for moving said members simultaneously and relatively for forcing the cutter elements through the material of the insulator.

17. In a machine of the character described, the combination of a stationary supporting structure, a carriage movably mounted thereon, means for moving the carriage, members pivoted on the carriage, lever operated means for moving said members, and cutting elements carried by the members.

18. In a machine of the character described, a stationary support, a carriage vertically movable thereon, means for moving the carriage, members pivoted on the carriage, means connecting said members for substantially simultaneous movement, means for moving said members, and coacting cutter elements carried by said members.

19. In a machine of the character described, a supporting structure, pairs of members pivotally mounted thereon and carrying cutter elements, means for moving said members, and means connecting said members and permitting relative movement between the pairs thereof.

20. In a machine of the character described, a supporting structure, pairs of members pivoted thereon, curved cutter elements carried by the respective members, means for moving said members substantially simultaneously, and means connecting the members of the pairs for permitting limited relative movement thereof.

21. In a machine of the character described, a supporting structure, pairs of members pivoted thereon, curved cutter elements carried by the respective members, means for moving said members substantially simultaneously, and means connecting the members of the pairs for permitting limited relative movement thereof for bringing the cutter elements carried thereby into interfitting relation.

22. In a machine of the character described, a supporting structure, stop elements carried thereby, outer and inner members pivoted on the supporting structure, the former being engageable with said stop elements, means for swinging said members, means permitting movement of the inner members with respect to the outer members, and cutter elements carried by the respective members and movable in an arcuate path.

23. In a machine of the character described, a support, stop elements, outer and inner members pivoted for movement in a vertical plane, the outer members being engageable with said stops, means connecting the outer and inner members for moving the same together and permitting limited relative movement of the inner members with respect to the outer, and cushioning means car-

ried by the outer members and coacting with said connecting means.

24. In a machine of the character described, a support, stop elements, outer and inner members pivoted for movement in a vertical plane, the outer members being engageable with said stops, means connecting the outer and inner members for moving the same together and permitting limited relative movement of the inner members with respect to the outer, cushioning means carried by the outer members and coacting with said connecting means, and means for adjusting said cushioning means.

25. In a machine of the character described, a stationary support, a carriage, means for moving the carriage, members pivoted on the carriage and carrying cutters adapted to be moved in an arcuate path, connecting elements connecting said members in pairs and permitting limited relative movement, divergent arm members pivotally connected with said connecting members, and means connected with said arm members for moving the same.

26. In a machine of the character described, a stationary support, a carriage, means for moving the carriage, members pivoted on the carriage and carrying cutters adapted to be moved in an arcuate path, connecting elements connecting said members in pairs and permitting limited relative movement, divergent arm members pivotally connected with said connecting members, means connected with said arm members for moving the same, comprising a vertically movable rack bar pivotally connected with said arm, and gear means for moving the rack bar.

27. In a machine of the character described, a supporting structure, means for mounting an insulator temporarily thereon, a carriage slidably mounted on the supporting structure, means for counterbalancing the carriage, cutters movably carried by the carriage, and means for moving the cutters in a curved path through the insulator to form a curved passage therethrough.

28. In a machine of the character described, a supporting structure, means for temporarily mounting an insulator thereon, a carriage slidable on the supporting structure, a rack bar, gear means for moving the rack bar, yoke members pivoted on the carriage, operative connections between the yoke members and the rack bar for swinging the yoke members in accordance with movement of the rack bar, and curved cutters carried by said yoke members and adapted to be moved in a curved path through the material of the insulator to form a curved passage therethrough.

29. In a machine of the character described, a stationary supporting structure, means for temporarily supporting an insulator thereon, an operating member slidably

- mounted with respect to the supporting structure, yoke members pivoted with respect to the supporting structure and carrying tubular curved cutters, link connections between 5 said operating member and said yoke members, and means for moving said operating member longitudinally to swing said yokes for forcing the cutters through the material of the insulator in a curved path.
- 10 30. In a machine of the character described, a stationary supporting structure, means for temporarily supporting an insulator thereon, an operating member slidably mounted with respect to the supporting structure, yoke members pivoted with respect to the supporting structure and carrying tubular curved cutters, link connections between 15 said operating member and said yoke members, means for moving said operating member longitudinally to swing said yokes for forcing the cutters through the material of the insulator in a curved path, and means for adjusting the length of said links for varying or adjusting the throw of the yoke members.
31. In a machine of the character described, a stationary supporting structure, means for temporarily supporting an insulator thereon, an operating member slidably mounted with respect to the supporting structure, yoke members pivoted with respect to the supporting structure and carrying tubular curved cutters, link connections between 35 said operating member and said yoke members, means for moving said operating member longitudinally to swing said yokes for forcing the cutters through the material of the insulator in a curved path, and stops forming part of the stationary structure and 40 engageable by certain of the yoke members for limiting outward swinging movement thereof.
32. In a machine of the character described, a relatively stationary supporting structure, a plurality of pairs of yoke members pivoted with respect thereto, the respective pairs of yoke members carrying coacting cutter sections, means for swinging said yoke members simultaneously, and means operatively connecting the pairs of yoke members 45 for moving them relatively during their simultaneous movement whereby the cutter sections will be moved relatively.
33. In a machine of the character described, a relatively stationary supporting structure, means for temporarily mounting an insulator thereon, pairs of yoke members pivotally mounted with respect to the supporting structure, coacting cutter sections 50 carried by the respective pairs of yoke members, links pivotally connecting the respective yoke members for permitting relative movement thereof, and means connected with said links for effecting swinging movement of 55 the yoke members simultaneously.
34. In a machine of the character described, a relatively stationary supporting structure, means for temporarily mounting an insulator thereon, pairs of yoke members pivotally mounted with respect to the supporting structure, coacting cutter sections carried by the respective pairs of yoke members, links pivotally connecting the respective yoke members for permitting relative movement thereof, and means connected with said 70 links for effecting swinging movement of the yoke members simultaneously, said links having portions engageable with the yoke members of one pair.
35. In a machine of the character described, a relatively stationary supporting structure, means for temporarily mounting an insulator thereon, pairs of yoke members pivotally mounted with respect to the supporting structure, coacting cutter sections 75 carried by the respective pairs of yoke members, links pivotally connected with the yoke members of the other pair, said link members having extensions thereon, and yieldable abutments on said second named pair of yoke members engageable by 80 said extensions.
36. In a machine of the character described, a relatively stationary supporting structure, means for temporarily mounting an insulator thereon, a carriage slidably mounted upon said supporting structure, a plurality of yoke members pivoted on said carriage and carrying curved cutters, a rack 85 bar slidably mounted within the carriage, operative connections between the rack bar and said yoke members, and an operating shaft carrying a gear meshing with said rack bar.
37. In a machine of the character described, means for temporarily mounting an insulator thereon in plastic condition, curved cutters, and means for forcing the cutters in opposite directions through the insulator.
38. In a machine of the character described, means for temporarily supporting an insulator in plastic condition, curved cutters, and means for simultaneously moving the cutters in opposite directions through the material of the insulator into end to end relation.
39. In a machine of the character described, means for temporarily supporting an insulator in plastic condition, curved cutters, means for simultaneously moving the cutters in opposite directions through the material of the insulator into end to end relation, and means for expanding the cutters during a portion of their movement.
40. In a machine of the character described, a curved cutter, means for temporarily supporting an insulator in plastic condition, means for moving the cutter in a curved path through the material of the insulator, and means for expanding and 125 connecting the cutter to the insulator.

tracting the cutter at different stages of its movement.

41. In a machine of the character described, means for temporarily supporting an insulator in plastic condition, curved cutters, and means for forcing the cutters through the material of the insulator for forming a curved passage having eccentric walls.

10 42. In a machine of the character described, means for temporarily supporting an insulator in plastic condition, curved cutters, means for moving the curved cutters into end to end relation through the material 15 of the insulator, and means for expanding portions of the cutters for flaring the ends of the curved passage formed thereby.

43. In a machine of the character described, means for temporarily supporting an insulator in plastic condition, curved cutters, means for forcing the curved cutters through the material of the insulator into end to end relation, and means carried by 20 one cutter movable into the other for puncturing the division wall remaining between 25 the ends of the cutters.

44. In a machine of the character de-

scribed, means for temporarily supporting an insulator in plastic condition, curved cutters, means for moving the cutters in a curved path through the material of the insulator into end to end relation, means for moving the cutters in the opposite direction to withdraw them from the insulator, and means for preventing the development of suction within the passages formed by the cutters when the cutters are withdrawn therefrom.

45. In a machine of the character described, means for temporarily supporting an insulator in plastic condition, curved cutters, means for initially expanding the cutters, means for moving the expanded cutters into the material of the insulator, and means for simultaneously moving the cutters in a curved path and contracting the same.

46. In a machine of the character described, means for supporting an insulator in plastic condition, a curved cutter, means for forcing the cutter in a curved path through the material of the insulator, and means for expanding and contracting the cutter at different times.

In testimony whereof I affix my signature.

STEWART L. MOORE, JR.
